UNITED STATES PATENT OFFICE.

WILLIAM J. ROCHE, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,210,209.

Specification of Letters Patent. Patented Dec. 26, 1916.

Application filed June 22, 1914. Serial No. 846,591.

To all whom it may concern:

Be it known that I, WILLIAM J. ROCHE, a resident of Meadville, in the county of Crawford and State of Pennsylvania, have 5 invented a new and useful Improvement in Garment-Stays, of which the following is a specification.

This invention relates to wire garment stays and more particularly to corset stays.

10 The object of the invention is to provide a flexible wire stay which yields readily in all directions, in which the bending strains are distributed over a considerable length of wire, so as to avoid crystallization and 15 deterioration of the metal and prevent the stay from taking a permanent set, in which the stay is reinforced along its edges, and particularly to provide a stay which is stronger and more resilient than prior stays 20 and offers more resistance to bending strains.

The invention comprises the stay herein-after described and claimed.

In the drawings, Figure 1 represents a 25 face view of one form of stay embodying the invention; Fig. 2 is a cross section thereof on the line 2—2, Fig. 1, and showing a modification; Fig. 3 is an edge view of the stay shown in Fig. 1; and Figs. 4 and 5 are 30 face views of modified forms of stay embodying the invention.

The stay shown in Figs. 1 to 4 of the drawing is formed from a single continuous wire 1 which is bent back and forth into 35 sinuous form to form a series of transverse portions 2 extending across from edge to edge of the stay, but may be formed of a plurality of wires, as shown in Fig. 5. Said transverse intermediate portions may be ex- 40 actly or nearly normal to the length of the stay, but as shown are at an angle thereto. At each end each of the crossing portions 2 is bent to form a small loop or eye 3, the loops or eyes at the ends of successive cross- 45 ings being connected at the edges of the stay by longitudinal connecting arched portions 4. These pairs of connected loops or eyes and the arched portions 4 lie in staggered relation to each other, and the wire of the 50 arched portions 4 is bent toward one flat side of the stay, as shown in Fig. 2.

The comparatively long crossing portions of the wire enable the stay to effectually withstand flatwise bending stresses which

are taken up largely by torsion in the wire 55 of the crossings, and the loops or eyes 3 and longitudinally extending arched portions 4 reinforce the edges of the stay and increase its resistance to edgewise bending strains in both directions.

The intermediate crossings or portions 2 may be deflected from a straight path across the stay in any suitable direction. For example, any or all of the crossings may be deflected toward one flat side of the stay, 65 as indicated in Fig. 2, to render the stay concavo-convex in cross section and give it more resistance to bending in one flatwise direction than in the other. Or, if desired, some or all of the crossings may be deflected 70 toward one or both ends of the stay in its flat plane, to form a series of small loops or convolutions 5 lying along the middle line of the stay. This increases the total amount of wire in the stay and gives it ad- 75 dditional resiliency and also strengthens the crossing portions of the wire due to the arched form of the loops or convolutions 5.

What I claim is:

1. A garment stay, comprising wire bent 80 back and forth to form a series of trans- 85 verse intermediate portions extending from edge to edge of the stay, adjacent intermediate portions at the edges of the stay being connected by arched portions extending lon- 85 gitudinally of the stay and out of the plane of the intermediate portions, and all of which arched portions being on the same face of the stay.

2. A garment stay, comprising wire bent 90 back and forth to form a series of trans- 95 verse portions or crossings extending from edge to edge of the stay, the wire at the ends of the crossings being deflected toward the center line of the stay to form a loop or eye at the end of each crossing, the loops or eyes at the ends of successive crossings being connected by arched portions extend- 100 ing longitudinally of the stay and out of the plane of the intermediate portions, and all of which arched portions being on the same face of the stay.

3. A garment stay, comprising wire bent back and forth to form a series of trans- 105 verse portions or crossings extending from edge to edge of the stay, the wire at the ends of the crossings being deflected toward the center line of the stay to form a loop or

eye at the end of each crossing, the loops or eyes at the ends of successive crossings being connected by arched portions extending longitudinally of the stay, said portions being arranged in two parallel longitudinal rows, the intermediate portions or crossings being deflected out of the plane of the stay from a straight line to form a series of loops or convolutions lying along the center line

of the stay between said rows of arched portions.

In testimony whereof, I have hereunto set my hand.

WILLIAM J. ROCHE.
